FOLDING MACHINE

Kurt Kaufmann, Tegel at Berlin, Germany, assignor to Automatic Aktiengesellschaft für automatische Druckmaschinen, Berlin, Germany

Application May 14, 1934, Serial No. 725,645
In Germany May 16, 1933

21 Claims. (Cl. 270—79)

My invention relates to folding machines, and more particularly to a machine for folding, before piling in zig-zag fashion, a web of paper or other material which is fed through a printing or other machine continuously or intermittently.

It is an object of my invention to so improve a folding machine of this type that it operates with absolute precision to crease the web exactly along a definite line, for instance, a row of perforations.

To this end, I provide a main frame and a movable subsidiary frame which may be mounted to oscillate about suitable trunnions on the main frame. The subsidiary frame is moved alternately in opposite directions by any suitable means. It supports a gate through which the web moves, and means such as a pair of rollers for feeding the web through the gate. At the two points where the movement of the subsidiary frame is reversed, positive folding means are arranged in fixed positions for creasing and folding about the lower edge of the gate the web which issues from the gate. "Positive" folding means are means whose members invariably perform the same movement with respect to the gate on the subsidiary frame for a given adjustment of the machine, without the intercession of springs and other elastic means. The precise operation required can only be obtained with such folding means.

In a machine for folding cloth which has previously been pleated, it has already been proposed to provide a pair of parallel folding knives, each mounted to oscillate about a pivot, like the oscillating subsidiary frame of my machine, for cooperation with a rocking table and holding jaws at both ends of the table. Each knife folds the pleated cloth between one end of the rocking table, and the jaw at that end, but these folding means are not positive since the rocking table is mounted on springs which are compressed in proportion to the number of folds between the table and the jaws, and so the position of the table with respect to the folding knives is variable. This may be harmless in a cloth-folding machine but must not be tolerated in my machine as it would interfere with the precision required.

In the accompanying drawings, a machine embodying my invention and equipped with an oscillating subsidiary frame, is illustrated more or less diagrammatically by way of example.

In the drawings

Figs. 1, 2, and 3 are elevations of the machine showing the oscillating subsidiary frame in its

central position, and at the rear and front ends, or reversing points, of its stroke, respectively.

Figs. 1a, 2a, and 3a show the lower end of the subsidiary frame, drawn to a larger scale, and in the positions of Figs. 1, 2, and 3.

Fig. 4 is a section on the line IV—IV, and

Fig. 5 is a section, drawn to a larger scale, on the line V—V, in Fig. 1.

Fig. 6 is a section on the line VI—VI in Fig. 5.

Fig. 7 is a section on the line VII—VII in Fig. 3a.

Fig. 8 is a section on the line VIII—VIII in Fig. 7, and

Fig. 9 is a plan view of a folding means.

Referring now to the drawings, the main frame 1 of the folding machine which may be part of, or attached to, a printing machine, or the like, comprises two side plates 1' and 1'', as best seen in Fig. 4. In Figs. 1, 2, and 3, the main frame is shown in dot- and dash-lines, as otherwise it would conceal the parts between its side plates. The driving shaft 31, Fig. 4, is mounted to rotate in the side plates 1' and 1'' beyond which its ends project. On the end which projects beyond the side plate 1'', is mounted a sprocket 31', or a pulley, or some other member, for rotating the shaft. On the opposite end of the shaft, beyond the side plate 1', is mounted a cam plate 32 for imparting oscillation to the subsidiary frame 2, and between the side plates and nearer to the side plate 1'', is mounted another cam plate 36 for operating a control on the subsidiary frame by which control the folding means are operated.

The subsidiary frame 2 has two arms 2' and 2'', braced by a pair of stays 4, 15, and, at its upper end, is mounted to oscillate about trunnions 3' and 3''. The trunnion 3' has its bearing in the side plate 1', and the trunnion 3'' has its bearing in a lug 1''' which is attached to, or integral with, the side plate 1''. The upper stay 4 connects two lugs 5' and 5'' on the respective arms 2' and 2'' of the subsidiary frame 2.

The gate is supported by the lower ends of arms 2', 2''. It comprises a pair of bars 6 and 6', of angle section, as best seen in Fig. 8 and tongues 7, 8 preferably made of thin steel plate, and projecting like racks with their lower ends, as shown in Figs. 4 and 7.

The web-feeding means which is also supported by the lower ends of arms 2', 2'', comprises a driven roller 9, Figs. 5 and 8, of larger diameter, and an idle roller 10, of smaller diameter. The means for driving the larger roller 9 will be described below. Both rollers are grooved for the reception of the tongues 7 and 8.

The shaft of the driven roller 9 is mounted to

rotate in the arms 2' and 2'' of the subsidiary frame 2, as shown in Fig. 5. The shaft 13 of the idle roller 10 is mounted to rotate in the lower ends of a pair of arms 14 whose upper ends are 5 pivoted about the lower stay 15. Means are provided for holding the roller 10 against the web 27 which is between the rollers, under resilient pressure. Such means comprise a laminated spring 16, Fig. 1a, on every arm 14, a bracket 18 10 per spring which bracket is clamped on the lower stay 15, and a set screw in the bracket whose shank 17 bears on the free end of the corresponding spring 16. By these means, the arms 14 are permanently forced toward the roller 9 under 15 the pressure of springs 16.

The web 27 moves through the machine from the right to the left in Figs. 1, 2, and 3. It is introduced by a pair of delivery rollers 28, 28 which are intermittently rotated in the direction 20 of arrows 29, Fig. 1, by any suitable means, not shown, in such manner that rotation of the rollers occurs while the subsidiary frame 2 moves from one of its final positions or reversing points, Figs. 2 and 3, to about its central position, Fig. 1. 25 However, the delivery rollers may also be rotated during other periods, intermittently or continuously.

The rollers 28, 28 deliver the web 27 to a table 30 at whose rear end a shaft 25 is mounted to 30 rotate in the main frame 1. This shaft supports a pair of arms 26 at whose free ends a registering roller 24 is mounted to rotate. From the registering roller 24, the web 27 moves to a brake which comprises a plain lower roller 21 mounted to 35 rotate in the main frame 1, and a pair of rings 22, 22 on a shaft 23 which is mounted to rotate in the main frame 1 above the lower roller 21, Fig. 4, the web being engaged by the rings and the roller in order to impart tension to the web as it 40 is pulled forwards by the rollers 9 and 10 of the web-feeding means 11. The position of the registering roller may be varied within rather wide limits by turning the arms 26 about the axis of shaft 25. The final positions of the arms 26 45 are shown in dot-and-dash lines in Fig. 2. Thus, while the brake 21, 22 is in a fixed position, the position of the registering roller with respect to the brake may be varied within the limits set by the final positions of arms 26.

The web is threaded toward the web-feeding means 11 at the lower end of the subsidiary frame 2 between two guide bars 19 and 20 whose ends are secured in the trunnions 3' and 3'' in such 50 position that, in the axis of the trunnions, they are almost tangent, i. e., spaced apart for the thickness of the web 27 only. Owing to this position of the gap of bars 19, 20, the oscillation of the subsidiary frame 2 does not interfere with the feeding of the web by the feeding means 11. 55 The web leaves the web-feeding means 11 by passing through between the tongues 7, 8 of the gate, is folded by the folding means at the reversing points of the oscillating subsidiary frame 2, as will be described below, and finally piled, 60 zig-zag fashion, at P, Figs. 1 to 3, in a suitable 65 piling device, not shown.

The driving shaft 31, and its cam plates, rotate at uniform velocity and continuously, in the direction of the arrow 33, Figs. 1 to 3. The cam 70 plate 32 which is similar to a fly wheel, has a groove 34 in which engages a roller 35 at the end of the shorter arm 36 of a bellcrank on a shaft 37. The longer arm 38 of the bellcrank is slotted at 39 for the reception of a block 40 which slides 75 in the slot and may be fixed in any desired posi-

tion therein. The two arms of the bellcrank obviously may be made as a single member. One end of a link 42 is pivotally connected to the block 40 at 41, and its other end is pivotally connected to the free end of an arm 43 on the trunnion 3' of the subsidiary frame 2. By these means, the subsidiary frame 2 is oscillated in the direction of arrow 44, and in opposite direction, and the angle through which it oscillates, is determined by the position of block 40 in slot 39 of 10 arm 38, and varied within wide limits.

The oscillation of the subsidiary frame 2 is utilized for operating the web-feeding means 11 thereon. Secured to the side plate 1' is a rack 45 which is curved to an arc of a circle about 15 the axis of trunnions 3', 3'' and has teeth 47 on its lower, and teeth 48 on its upper edge. Pinions 49 and 50 on the subsidiary frame 2 mesh with the teeth 48 and are rotated as the frame oscillates. The pinion 49 is free to rotate 20 on an extension of the shaft 12 of driven roller 9 beyond the arm 2'. The pinion 50 is free to rotate on a shaft 51 in the arm 2'. A spur gear 52 is keyed on the shaft 12 and meshes with a spur gear 53, of equal diameter, which is free to 25 turn on the shaft 51. One-way clutches, of old design, are inserted between the pinions and spur gears which are on the same shafts.

Referring now to Fig. 6, the one-way clutch by 30 which the pinion 49 is connected to the spur gear 52 on the shaft 12, comprises a cage 54 keyed on the shaft 12, with recesses 55, balls 56 in the recesses, and springs 56' urging the balls onto the gradients of the recesses. The balls run on a race in the hollow boss of pinion 49. Rotation 35 of the pinion 49 in the direction of arrow 57 corresponds to movement of the subsidiary frame 2 in rearward direction, i. e., against arrow 44. The one-way clutch of pinion 49 is so designed that rotation of the pinion 49 in the direction 40 of arrow 57 causes the balls 56 to connect the pinion 49 to the shaft 12 and to the spur gear 52.

The one-way clutch for the pinion 50 is similar. Its cage 59, with recesses 58 for the balls 56, and springs 56', is integral with the spur gear 53 and arranged oppositely to the cage 54 on the shaft 12, so that the spur gear 53 is not rotated by the pinion 50 when the pinion rotates in the direction of arrow 57, while upon rotation of the pinion in the opposite direction, corresponding 50 to oscillation of subsidiary frame 2 in the direction 44, the pinion 50 is connected to the spur gear 53. The rotation of the pinion 50 is transferred to shaft 12 through spur gears 52 and 53. By these means, the roller 9 is driven in the same 55 direction for both directions of oscillation of subsidiary frame 2.

The positive folding means will now be described. The machine has two folding means 60 which, as mentioned, are arranged at the two points where the subsidiary frame 2 is reversed. The two folding means are quite similar, and only one of them will be described in full detail, corresponding parts of the other means being marked with the same reference numerals and 60 the index "'". The means for folding the web 27 at the front reversing point of the subsidiary frame 2, i. e., at the right in Figs. 1, 2, and 3, is equipped with a bracket 60, and the means at the rear reversing point is equipped with a 70 bracket 60'. As shown for the bracket 60 in Fig. 7, the brackets have lateral lugs 61 at opposite ends which bear on a curved track 62 of the rack 45, and on a curved track 62' of a member 46 which is similar to the rack 45 but 75

is without the teeth 48, and secured to the side plate 1" opposite the rack 45. Ribs 63, as best seen in Fig. 8, extend downwardly from opposite sides of bracket 60, and a shaft 64 is mounted 5 to rotate in the ribs 63. Pinions 65 and 65' are keyed on the ends of the shaft 64 and mesh, respectively, with teeth 47 and 47' on the lower sides of the rack 45 and the member 46. A clamp 75 on the bracket 60 surrounds the shaft 10 64 for fixing it in a definite position after rotating it, and the shaft has a flattened portion 66 to be engaged by a wrench or the like. The ribs 63 support wheels 67 and 67' which engage the tracks 62 and 62' from below.

15 A folding member 68, of triangular cross section, is arranged at the inner end of the bracket 60, i. e., at the end which faces the subsidiary frame 2. This folding member is mounted to turn about pivots 69 in the ribs 63, and a coiled 20 spring 70 at one end of the folding member, Fig. 9, tends to move the member into the position shown in dotted lines in Fig. 8 in which it is below the ends of tongues 7 and 8. A controlling 25 arm 71, with a roller 73 at its free end, is secured to the folding member 68 at that end which is opposite the spring 70. When the folding member 30 is in its turned-down position (dotted lines in Fig. 8), the roller 73 is in its topmost position from which it is moved into its lowermost position by a push rod on the subsidiary frame 2, as will be described below. The push rod positively moves the folding member 68 into its active position as shown in full lines in Fig. 8.

The upper faces of the brackets 60 and 60' 35 are recessed at 74 for the reception of the tooth-like portions of the tongues 7 and 8. The recesses 74 permit the tongues to move beyond the brackets 60, 60' and prevent damage to the tongues if the brackets have not been adjusted 40 in conformity with the stroke of the subsidiary frame 2. The adjustment of the brackets 60, 60' along the rack 45 and the member 46 is effected by rotating the shaft 64 through the medium of its flattened portion 66 so as to move every 45 bracket to the desired distance from the adjacent end of the rack or member. The brackets are fixed in the positions to which they have been moved, by setting the clamp 75 so that the shaft cannot be rotated further.

50 The push rod for positively operating the controlling arms 71, and the means for positively actuating the push rod, will now be described. A bell crank 80, 81 is pivoted in the side plate 1" at 82. Its arm 80 is equipped with a roller 79 at its free end, for cooperation with the cam plate 76 on the driving shaft 31. A spring 89 pulls the roller 79 into engagement with the cam plate 76. The cam plate has two diametrically opposite concentric portions and two, also diametrically opposite, depressions 77 and 78. A link 83 is pivotally connected to the end of the bellcrank arm 81 and the other end of the link is pivotally connected to the arm 84 of a bellcrank which is pivoted to the side plate 1" at 86. The other 55 arm 85 of the bellcrank is pivotally connected to a push rod 87 at the upper end of the push rod. The lower end of the push rod which is fork-shaped and has two lugs 87' and 87", is guided by a rocking arm 88 on the arm 2" of the subsidiary frame 2.

70 While the roller 79 at the end of bellcrank arm is held against one of the concentric portions of the cam plate 76 by the spring 89, the push rod 87 is in the position illustrated in Fig. 1 in which its upper end, where the rod is connected

to the arm 85, is exactly in line with the axis of trunnions 3', 3". The corresponding position of the lower end of the push rod is shown in Fig. 1a. When the roller 79 descends into one of the depressions 77 or 78, the spring 89, through the means described, causes the push rod to descend along the arm 2" in the direction of arrow 90, Fig. 1. This moves the lugs 87' and 87" into active relation to the rollers 73 on the controlling arms 71 of the folding members 68.

75 The operation of the machine is as follows:

Assume that the parts are in the positions illustrated in Figs. 1 and 1a, showing the central position of the subsidiary frame 2. As the cam plate 32 rotates with the shaft 31 in the direction 15 of arrow 33, the subsidiary frame 2 is moved toward the front reversing point in the direction of arrow 44. The configuration of the groove 34 in cam plate 31 is such that the subsidiary frame 2 moves more slowly when approaching one of its 20 reversing points, and after leaving the point, than during the balance of its oscillation, and is arrested for a short time at the reversing points.

The two positive folding means, with their 25 brackets 60 and 60', are adjusted on the rack 45 and the member 46 in the manner described and in conformity with the angle through which the subsidiary frame 2 oscillates. This angle is determined by the position of the block 40 in the slot 39 of bell crank arm 38, as described. If 30 properly adjusted, the inner ends of the brackets 60, 60' must be so positioned that, as shown for the bracket at the right in Fig. 8, the inner end 60" of the bracket is engaged by the web 27 which issues from between the tongues 7 and 8. 35 The tooth-like portions of the tongue 8 enter the recesses 74 in the bracket, while the tongue 7 is spaced apart from the inner end of the bracket. The same relation obviously holds good for the cooperation of the subsidiary frame with the 40 folding means at the left. As mentioned, the tongues 7 and 8 are not damaged but move freely in the recesses 74 if the brackets have not been adjusted exactly in conformity with the oscillation of the subsidiary frame.

45 When the subsidiary frame 2 has arrived at its front reversing point, Fig. 3, the roller 79 engages in the depression 78 of camplate 76, the push rod 87 descends in the direction of arrow 90, and its lug 87' engages the roller 73 of the controlling 50 arm 71 and moves it into the position best seen in Fig. 8, raising the folding member 68 about its pivots 69 into the full-lines position, and causing the member to sharply and positively crease the issuing paper web 27 about the lower 55 edge of the tongues 7. As the axis of the pivots 69 is at the rear of the inner end 60" of bracket 68, the folding member, in moving into its folding position, performs a certain displacement along the outer face of tongues 7 in upward direction, and the crease becomes sharper. The force which holds the folding member 68 against the tongues 7 and 8, and slightly bends the tongues until they bear against the inner end 60" of the bracket, is exerted by spring 89, as the depressions 77 and 78 are so shaped that the roller 79 is not yet at the bottom of the depression (78 in Fig. 3) when the downward movement of push rod 87 is terminated by the aforesaid positive engagement of the folding member with respect 60 to the inner end of the bracket. The fork shape of the push rod 87 permits it to clear the pivot 89 at the corresponding end of the bracket, and the non-active lug 87" to descend freely.

65 When the folding operation at the front re- 75

versing point has been completed, as shown in Fig. 8, the subsidiary frame 2 moves into the position illustrated in Fig. 2, against arrow 44, and through the central position of Fig. 1. Before 5 the subsidiary frame arrives at its rear reversing point, the push rod 87 is returned into its initial position by cam plate 76 and permits the spring 70 to return the folding member 68 into its initial position, dotted lines in Fig. 8; the web is now 10 piled at P as shown in Fig. 2, and the next folding operation is performed by the folding means at the left, as soon as the subsidiary frame 2 has attained its rear reversing point, and under the control of the other lug 87" of the push rod 87, as 15 shown in Fig. 2a.

During the oscillation of the subsidiary frame in the direction of arrow 44, as well as against the arrow, the web 27 is fed through the gate by the web-feeding means 11. In this manner, the 20 web 27 is deposited on the pile P zig-zag fashion and finish-folded, as the subsidiary frame oscillates.

As described, the web-feeding means 11 is driven by the pinion 50 when the subsidiary frame moves toward its front reversing point at the right, arrow 44. Through the spur gears 52, 53 the roller 9 is rotated in the direction of arrow 57. The idle roller 10 is rotated by friction from the driven roller 9. When the subsidiary frame moves 30 toward its rear reversing point at the left, against arrow 44, the roller 9 is rotated directly and in the same direction as before, by the pinion 49.

As often as the subsidiary frame 2 returns from one of its reversing points, the delivery rollers 28, 35 28 supply more material than is fed by the web-feeding means 11, and so the web 27 sags at 27', Fig. 1. When the subsidiary frame is in, or approximately in, its central position, the delivery rollers 28, 28 stop, and the feeding means 11 40 now winds up the sagging portion 27'. The sagging portion 27' is formed by a correspondingly rapid and intermittent operation of the delivery rollers 28, 28, and the sag is so determined that at every reversing point of the subsidiary frame the web is taut from the—then stopping—delivery rollers 28, 28, as far as the folding means which favors the formation of very sharp folds. With such sharp folds, the web is piled zig-zag fashion 45 on the pile P, without any auxiliary means.

It will be understood that the movement imparted to the roller 9 of the feeding means 11 through the rack 45 and the pinions 49, 50, is a function of the stroke of the subsidiary frame 2, and that the folding members 68 are operated. 50 when the subsidiary frame 2 is at the reversing points of its oscillation. In order to vary the pitch of the folds, the angle of oscillation is varied by shifting the block 40 in the slot 39 of lever 38, and the folding means are adjusted in conformity with the angle which has been selected. Obviously, the two folding means must be in positions corresponding to one half of the stroke 55 performed by the subsidiary frame 2.

The registering roller 24 at the ends of arms 28 60 is adjustable, as indicated in Fig. 2, and by such adjustment the web 27 may be so positioned that the folds are at definite points of the web, which is necessary, for instance, if the folds coincide with perforations, creases, etc.

70. I claim:

1. In a machine for folding webs to be piled zig-zag fashion, a main frame, a movable subsidiary frame on said main frame, means for alternately moving said subsidiary frame in opposite directions, a gate and web-feeding means

on said subsidiary frame, and positive folding means arranged in fixed positions at the two points where the movement of said subsidiary frame is reversed, for folding about the lower edge of said gate the web issuing therefrom. 5

2. In a machine for folding webs to be piled zig-zag fashion, a main frame, a movable subsidiary frame on said main frame, means for alternately moving said subsidiary frame in opposite directions, a gate and web-feeding means on 10 said subsidiary frame, means for operating said web-feeding means in the same direction for both directions of movement of said subsidiary frame, and folding means arranged in fixed positions at the two points where the movement of said subsidiary frame is reversed, for folding about the lower edge of said gate the web issuing therefrom. 15

3. In a machine for folding webs to be piled zig-zag fashion, a main frame, a movable subsidiary frame on said main frame, means for alternately moving said subsidiary frame in opposite directions, means for varying the stroke imparted to said subsidiary frame, a gate and web-feeding means on said subsidiary frame, folding means arranged in fixed positions at the two points 20 where the movement of said subsidiary frame is reversed, for folding about the lower edge of said gate the web issuing therefrom, and means for varying the position of said folding means in conformity with the various strokes imparted to 25 said subsidiary frame.

4. In a machine for folding webs to be piled zig-zag fashion, a main frame, a movable subsidiary frame on said main frame, means for alternately moving said subsidiary frame in opposite directions, a gate and web-feeding means on 30 said subsidiary frame, folding means arranged in fixed positions at the two points where the movement of said subsidiary frame is reversed, for folding about the lower edge of said gate the web 35 issuing therefrom, and means on said subsidiary frame for controlling said folding means.

5. In a machine for folding webs to be piled zig-zag fashion, a main frame, a subsidiary frame mounted to oscillate on said main frame, means for oscillating said subsidiary frame, a gate and web-feeding means on said subsidiary frame, means arranged in the axis about which said subsidiary frame oscillates, for guiding a web to 40 said web-feeding means, and folding means arranged in fixed positions at the two points where the movement of said subsidiary frame is reversed, for folding about the lower edge of said gate the web 45 issuing therefrom.

6. In a machine for folding webs to be piled zig-zag fashion, a main frame, a subsidiary frame mounted to oscillate on said main frame, means for oscillating said subsidiary frame, intermittently operated means for feeding a web to said subsidiary frame, a gate and web-feeding means 50 on said subsidiary frame, means for continuously operating the web-feeding means on said subsidiary frame, and folding means arranged in fixed positions at the two points where the movement of said subsidiary frame is reversed, for folding about the lower edge of said gate the web 55 issuing therefrom.

7. In a machine for folding webs to be piled zig-zag fashion, a main frame, a subsidiary frame mounted to oscillate on said main frame, means for oscillating said subsidiary frame, a gate on 60 said subsidiary frame, a web-feeding roller mounted for rotation in said subsidiary frame, means for rotating said web feeding roller, a pair of arms pivoted to said subsidiary frame, an idle 65 roller, and folding means arranged in fixed positions at the two points where the movement of said subsidiary frame is reversed, for folding about the lower edge of said gate the web 70 issuing therefrom.

5 roller supported by said arms, resilient means for urging said idle roller toward said web-feeding roller, and folding means arranged in fixed positions at the two points where the movement of said subsidiary frame is reversed, for folding about the lower edge of said gate the web issuing therefrom.

10 8. In a machine for folding webs to be piled zig-zag fashion, a main frame, a subsidiary frame mounted to oscillate on said main frame, means for oscillating said subsidiary frame, a gate on said subsidiary frame, a web-feeding roller mounted for rotation in said subsidiary frame, means including one-way clutches for rotating said web-feeding roller in the same direction for the opposite directions in which said subsidiary frame oscillates, and folding means arranged in fixed position at the two points where the movement of said subsidiary frame is reversed, for 15 folding about the lower edge of said gate the web issuing therefrom.

20 9. In a machine for folding webs to be piled zig-zag fashion, a main frame, a subsidiary frame mounted to oscillate in said main frame, means for oscillating said subsidiary frame, a gate on said subsidiary frame, a web-feeding roller mounted for rotation in said subsidiary frame, a rack secured to said main frame and curved to the arc of a circle about the axis of oscillation of 25 said subsidiary frame, a pair of pinions meshing with said rack, a spur gear on said web-feeding roller, in axial alignment to one of said pinions, another spur gear meshing with said first-mentioned spur gear and arranged in axial alignment 30 to the other pinion, one-way clutches acting in opposite directions and connecting said pinions to the spur gears to which they are axially aligned, for rotating said web-feeding roller in the same direction for the opposite directions in which said subsidiary frame oscillates, and folding means arranged in fixed positions at the two points where the movement of said subsidiary frame is reversed, for folding about the lower edge of said gate the web issuing therefrom.

35 10. In a machine for folding webs to be piled zig-zag fashion, a main frame, trunnions in said main frame, a subsidiary frame mounted to oscillate about said trunnions, means for oscillating said subsidiary frame, a gate and web-feeding means on said subsidiary frame, a pair of guide bars between said trunnions for guiding a web to said web-feeding means, with the interstice of said guide bars arranged in the axis of said trunnions, and folding means arranged in fixed positions at the two points where the movement of said subsidiary frame is reversed, for folding about the lower edge of said gate the web issuing therefrom.

40 11. In a machine for folding webs to be piled zig-zag fashion, a main frame, trunnions in said main frame, a subsidiary frame mounted to oscillate about said trunnions, means for oscillating said subsidiary frame, a gate and web-feeding means on said subsidiary frame, a pair of guide bars between said trunnions for guiding a web to said web-feeding means, with the interstice of said bars arranged in the axis of said trunnions, web-braking means arranged in advance of said guide bars, a registering roller for the web arranged in advance of said web-braking means, means for displacing said registering roller with respect to said web-braking means, and folding means arranged in fixed positions at the two points where the movement of said subsidiary 45 frame is reversed, for folding about the lower

edge of said gate the web issuing therefrom.

5 12. In a machine for folding webs to be piled zig-zag fashion, a main frame, a subsidiary frame mounted to oscillate on said main frame, means for oscillating said subsidiary frame, a gate on said subsidiary frame, tongues in said gate which are spaced apart for the reception of the web between them, web-feeding means including a pair of rollers, also on said subsidiary frame, the gap between said rollers being positioned in the region of the upper ends of said tongues, and folding means arranged for cooperation with the lower ends of said tongues, in fixed positions at the two points where the movement of said subsidiary frame is reversed.

10 13. In a machine for folding webs to be piled zig-zag fashion, a main frame, a subsidiary frame mounted to oscillate on said main frame, means for oscillating said subsidiary frame, a gate and web-feeding means on said subsidiary frame, a 20 track on said main frame which is curved to the arc of a circle about the axis of oscillation of said subsidiary frame, a pair of brackets mounted to move on said track, means for holding said brackets in definite positions from the ends of said track, each bracket having an inner end adapted to be engaged by said gate in the corresponding reversing position of said subsidiary frame, a folding member pivotally connected to each bracket in the vicinity of said inner end, means for holding said folding members in inactive position, and means on said subsidiary frame for moving said members into active position for cooperation with said gate, so as to fold the web issuing from said gate about the lower edge of said gate.

15 14. In a machine for folding webs to be piled zig-zag fashion, a main frame, a subsidiary frame mounted to oscillate on said main frame, means for oscillating said subsidiary frame, a gate and web-feeding means on said subsidiary frame, 40 folding means each including a pivoted folding member and a controlling arm operatively connected to said member; and arranged in fixed positions at the two points where the movement of said subsidiary frame is reversed, a push rod on said subsidiary frame which is adapted to cooperate with one of said controlling arms at a time, and means for moving said push rod into active position with respect to the corresponding controlling arm when said subsidiary frame is at 45 a reversing point.

20 15. In a machine for folding webs to be piled zig-zag fashion, a main frame, a subsidiary frame mounted to oscillate on said main frame, means for oscillating said subsidiary frame, a gate and web-feeding means on said subsidiary frame, folding means each including a pivoted folding member and a controlling arm operatively connected to said member; and arranged in fixed positions at the two points where the movement of said subsidiary frame is reversed, a push rod on said subsidiary frame which is adapted to cooperate with one of said controlling arms at a time, a bellcrank pivoted on said main frame, a pivotal connection of one arm of said bellcrank and said 60 push rod, said bellcrank being so positioned that in the central position of said subsidiary frame said pivotal connection is in the axis said subsidiary frame oscillates about, a link pivotally connected to the other arm of said bellcrank, 65 and means operatively connected to said link for moving said push rod into active position with respect to the corresponding controlling arm when said subsidiary frame is at a reversing point.

25 16. In a machine for folding webs to be piled 70 75

zig-zag fashion, a main frame, a subsidiary frame mounted to oscillate on said main frame, means for oscillating said subsidiary frame, a gate and web-feeding means on said subsidiary frame, 5 folding means each including a pivoted folding member and a controlling arm operatively connected to said member; and arranged in fixed positions at the two points where the movement of said subsidiary frame is reversed, a push rod 10 on said subsidiary frame, a pair of lugs on the forked lower end of said push rod, one of said lugs being adapted to cooperate with one of said controlling arms at a time while the other lug clears the pivotal connection of said folding member 15 to said folding means, and means for moving said push rod into active position of its lugs with respect to the corresponding controlling arm when said subsidiary frame is at a reversing point.

17. In a machine for folding webs to be piled 20 zig-zag fashion, a main frame, a subsidiary frame mounted to oscillate on said main frame, means for oscillating said subsidiary frame, a gate and web-feeding means on said subsidiary frame, rack-like tongues on said gate, folding 25 means each including a bracket recessed for said tongues, a folding member pivoted to said bracket, and a controlling arm operatively connected to said member; and arranged in fixed 30 positions at the two points where the movement of said subsidiary frame is reversed, a push rod on said subsidiary frame which is adapted to cooperate with one of said controlling arms at a time, and means for moving said push rod into active position with respect to the corresponding controlling arm when said subsidiary frame is at a reversing point.

18. In a machine for folding webs to be piled 35 zig-zag fashion, a main frame, a subsidiary frame mounted to oscillate on said main frame, means for oscillating said subsidiary frame, a gate and web-feeding means on said subsidiary frame, rack-like tongues on said gate, folding means each including a bracket recessed for said 40 tongues, a folding member pivoted to said bracket at a point positioned in the arc described by the lower ends of said tongues, and at the rear of the inner end of said bracket, and a controlling arm operatively connected to said member; and arranged in fixed positions at the two 45 points where the movement of said subsidiary frame is reversed, a push rod on said subsidiary frame which is adapted to cooperate with one of said controlling arms at a time, and means for moving said push rod into active position 50 with respect to the corresponding controlling arm when said subsidiary frame is at a reversing point.

19. In a machine for folding webs to be piled 55 zig-zag fashion, a main frame, a subsidiary

frame mounted to oscillate on said main frame, means for oscillating said subsidiary frame, a gate and web-feeding means on said subsidiary frame, a pair of rails on said main frame which are curved to the arc of a circle about the axis of oscillation of said subsidiary frame, a pair of brackets, lugs on said brackets for supporting them on said rails, teeth on said rails, pinions mounted to rotate on said brackets and meshing with said teeth, means for rotating said pinions so as to move said brackets along said rails, a pivoted folding member, and a controlling arm operatively connected to said member on each bracket, a push rod on said subsidiary frame which is adapted to cooperate with one of said controlling arms at a time, and means for moving said push rod into active position with respect to the corresponding controlling arm when said subsidiary frame is at a reversing point.

20. In a machine for folding webs to be piled 20 zig-zag fashion, a main frame, a subsidiary frame mounted to oscillate on said main frame, means for oscillating said subsidiary frame, a gate and web-feeding means on said subsidiary frame, a pair of rails on said main frame which 25 are curved to the arc of a circle about the axis of oscillation of said subsidiary frame, a pair of brackets, lugs on said brackets for supporting them on said rails, teeth on said rails, pinions mounted to rotate on said brackets and meshing with said teeth, means for rotating said pinions so as to move said brackets along said rails, means for holding said pinions against rotation, a pivoted folding member, and a controlling arm operatively connected to said member on each bracket, a push rod on said subsidiary frame which is adapted to cooperate with one of said controlling arms at a time, and means for moving said push rod into active position with respect to the corresponding controlling arm when said subsidiary frame is at a reversing point.

21. In a machine for folding webs to be piled 30 zig-zag fashion, a main frame, a movable subsidiary frame on said main frame, means for alternately moving said subsidiary frame in opposite directions, a gate on said subsidiary frame including a pair of parallel gate members spaced apart for the reception of a web between them, means, also on said subsidiary frame, for feeding the web through said gate between its members, and positive folding means arranged in fixed positions at the two points where the movement of said subsidiary frame is reversed, for creasing about the lower edge of one of said gate members the web issuing from between said gate members.

KURT KAUFMANN.
